(57) **CLAIM**

The ornamental design for an aircraft cabin controller, as shown and described.

DESCRIPTION

FIG. 1 is a front, right perspective view showing an aircraft cabin controller according to our design;

FIG. 2 is a right side elevation view thereof, the left side being a mirror image thereof;

FIG. 3 is a front elevation view thereof; and,

FIG. 4 is a top plan view thereof.

The broken lines shown in FIG. 1 illustrate environmental structure and form no part of the claimed design. The solid jagged line shown in FIG. 1 is used to show the cutoff of the broken line disclosure and forms no part of the claimed design.
